ALEXANDER K. SUTHERLAND, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

KNIFE-SWITCH BLADE.

1,078,523.

Specification of Letters Patent. Patented Nov. 11, 1913.

Application filed January 10, 1913. Serial No. 741,239.

To all whom it may concern:

Be it known that I, ALEXANDER K. SUTHERLAND, a citizen of the United States, residing at Plainville, county of Hartford, 5 State of Connecticut, have invented an Improvement in Knife-Switch Blades, of which the following is a specification.

This invention has for its object to simplify, cheapen and to greatly strengthen the 10 construction of the blades of knife switches, whether used singly or a plurality of blades are attached to an insulating bar.

With these ends in view the invention consists in the novel construction and combination of parts which I will now describe and then specifically point out in the claim hereunto appended.

In the accompanying drawing forming a part of this specification, Figure 1 is an elevation showing a plurality of knife switch blades attached to an insulating bar in accordance with my present invention; Fig. 2 an end view corresponding therewith; Fig. 3 an elevation showing a single blade with a 25 handle attached; Fig. 4 an elevation on an enlarged scale of a blade detached, the holding piece being shown in section and assembled with the blade but not attached thereto; Fig. 5 a section on the line 5—5 in Fig. 4; Fig. 6 a section corresponding therewith showing the holding piece attached to the blade; Fig. 7 an elevation corresponding with Fig. 6 showing the holding piece attached to the blade; Fig. 8 an elevation from 35 a point of view at right angles to that in Fig. 7; Fig. 9 an elevation, on an enlarged scale, partly in section, corresponding with Fig. 3; Fig. 10 is a perspective view of the holding piece detached; and Fig. 11 is an 40 elevation of the base of the blade showing a certain variation in the details of construction.

20 denotes a blade which is provided near its handle end with recesses 21, which may 45 extend inward from opposite edges as in Fig. 4, or may be holes through the blade as in Fig. 11. 22 denotes the holding piece which is U-shaped in cross section; that is a block of metal provided with a longitudinal 50 slot 23 in which the end of the blade is

seated. After assembling the blade and holding piece as in Figs. 4 and 5, they are rigidly secured together by swaging the metal of the holding piece into the recesses in the blade as clearly shown in Figs. 6, 7 55 and 8. This swaging operation may be accomplished in any ordinary or preferred manner as by subjecting the assembled parts to one or more blows in a drop press. This results in a practically solid blade having an 60 enlarged head which may be drilled and tapped for attachment to an insulating bar 24 (see Figs. 1 and 2) or for attachment to a handle 25 as in Figs. 3 and 9. Where an insulating bar is used, as in Figs. 1 and 3, 65 the blades may be attached to the bar by means of screws 26 which pass through the bar and have threaded engagement with the attaching piece. Where an uneven number of blades is used the threaded stem 27 of the 70 handle passes through the bar and has threaded engagement with the holding piece of the central blade, as clearly shown in Fig. 1. Where a single blade is used the threaded stem of the handle has threaded engagement with the holding piece, as clearly 75 shown in Fig. 9.

The present construction does away with the present system of attaching the blades to blocks by means of rivets and greatly 80 strengthens the switches. It is of course well understood that switches of this class are usually closed with considerable force which tends to shear the rivets and to loosen the blocks. 85

Having thus described my invention I claim:

A knife switch blade comprising a blade provided near its handle end with recesses and an attaching piece having a longitudinal 90 slot in which the blade is seated, the parts being secured together by swaging the ends of the metal of the attaching piece on each side of the slot into the recesses.

In testimony whereof I affix my signature 95 in presence of two witnesses.

ALEXANDER K. SUTHERLAND.
